United States Patent Office.

THOMAS LAMB, OF PHILADELPHIA, PENNSYLVANIA.

Letters Patent No. 98,390, dated December 28, 1869.

IMPROVEMENT IN SEWING-MACHINE.

The Schedule referred to in these Letters Patent and making part of the same

To all whom it may concern:

Be it known that I, THOMAS LAMB, of Philadelphia, Pennsylvania, have invented certain Improvements in Sewing-Machines; and I do hereby declare the following to be a full, clear, and exact description of the same.

My invention consists of certain improvements, fully described hereafter, in that class of lock-stitch sewing-machines, in which discoidal shuttles are used.

In order to enable others skilled in the art to make and use my invention, I will now proceed to describe its construction and operation, reference being had to the accompanying drawing, which forms a part of this specification, and in which—

Figure 1 is a longitudinal sectional view of my improved sewing-machine;

Figure 2, an end view of the same;

Figure 3, transverse section on the line 1-2, fig. 1, looking in the direction of the arrow;

Figure 4, a plan view, showing the edge of the shuttle;

Figures 5, 6, and 7, detached views, illustrating my invention; and

Figure 8, a modification.

Similar letters refer to similar parts throughout the different views.

A is the base-plate of the machine, in projections *a a*, beneath which turns the driving-shaft B, the latter being provided, near its rear end, with an eccentric, C, by means of which, and an arm, X, shown by dotted lines in fig. 1, the necessary reciprocating motion is imparted to the needle-arm D.

At the front end of the shaft B is a forked driver, c, by which the discoidal shuttle F is rotated, the latter being arranged at an angle, as shown in fig. 1, and turning in an inclined race.

This shuttle-race consists of two plates E and E', each of which is curved so as to fit against and enter a groove of the shuttle, the two plates being secured to a hanger, M, which projects at an angle from the under side of the base-plate.

In consequence of the inclination of the shuttle-race, the prongs of the driver, as they rotate, alternately enter and are withdrawn from holes *b b* on the face of the shuttle, neither of them being in permanent contact with the latter, and offering no obstruction to the passage of the loop of needle-thread around the shuttle, as will be more fully described hereafter.

The nose or hook *d* of the shuttle is formed by cutting away a portion of the circumference of the same, as clearly shown in fig. 4; and, secured to the centre of the inner face of the shuttle, by a screw or otherwise, is an adjustable projection or hook, e, having, at its outer end, a bevelled edge, e', for a purpose described hereafter.

At the upper end of the plate E of the shuttle-race is a bevelled projection, f, the object of which is to push the loop of needle-thread over the hook *d*, and to direct it to each side of the shuttle, as shown in fig. 2.

A rod, h, is secured to the plate E of the race, and projects over a portion of the inner face of the shuttle, and on the opposite side of the shuttle is a recess for the reception of a bobbin, G, which, in the present instance, is held in its place by a plate or case, i, the edge of which fits loosely in a groove in the shuttle, the case, however, not turning with the latter.

The shuttle-thread from the bobbin G passes through one or more openings *i* in the plate *i*, according to the tension required.

The presser-foot H is attached to one end of a recessed arm, I, which is curved in the arc of a circle, and secured, at its opposite end, to a plate, J, the latter being arranged to turn upon trunnions *j j* of the base-plate, and being elevated, at its rear end, by a spring, k, which tends to hold the presser-foot down to the work-plate l.

The feeding-dog K is also secured to a curved arm, L, which is arranged to slide in the recess *m* of the arm I.

A lug, p, is attached to the needle-arm D by a setscrew, or otherwise, so that it may readily be adjusted thereon, and is arranged, when the needle-arm is raised, to strike a pin, q, fig. 7, which enters the recess *m* of the arm I, and has secured to it, within the said recess, a wedge-shaped block, q'.

One side of this block *q'* bears against the inclined end of the arm L, and its opposite side against the inclined end of a plate, r, which is slotted, and has a slight motion within the recess *m*, limited by a pin, r'.

A spring, s, of the arm I, figs. 2 and 3, bears against one side of the feeding-dog arm, and tends to push it from the recess *m*, the feed being effected by a lateral pressure in the opposite direction, imparted by a lever, t, which is hung to the arm I.

The lever *t* is provided with a curved arm, t', which partly embraces the needle-arm, so that when the latter is raised, a pin, u, of the same, shall strike and turn the arm *t'*, causing the lever *t* to bear against and operate the feed-dog K.

Operation.

When the needle descends through the fabric to be sewed, and toward the shuttle, the hook *d* of the latter passes between the needle and its thread, and carries the loop toward the bevelled projection *f*, which, as before mentioned, pushes the loop back on to the hook *d*, and directs it to each side of the shuttle, as seen in figs. 2, 3, and 4.

The shuttle continues to revolve, carrying the loop with it, and the needle descends to the lowest point,

and again rises until it is entirely withdrawn from the cloth, as shown in fig. 5, at which time the presser-foot H is raised, and the feed-dog K depressed and moved laterally to a sufficient extent to effect the desired change of position of the cloth.

These motions of the presser-foot and feed-dog are effected simultaneously, as the needle is raised, by the lug p and pin u of the needle-arm, as I will now proceed to explain.

The lug p strikes the pin q, and forces the wedge-shaped block q' into the recess m of the arm I, the block bearing upon and causing the plate r and arm L to move in the direction of their respective arrows, fig. 7.

The motion of the plate r is arrested by the pin r', the plate J then turning upon its trunnions j until the arm I is moved sufficiently to raise the presser-foot clear of the cloth, as shown in fig. 2.

The arm L is in the mean time moved in a contrary direction, causing the under serrated surface of the feed-dog to bear upon the cloth.

As soon as these motions are perfected, the pin u of the needle-arm strikes the arm t' of the lever t, and causes the latter to bear upon and move the feed-dog laterally to the required extent.

When the needle again descends, the block q' is again released, and the spring k of the plate J bears upon the bed-plate, turns the arm I, and depresses the foot H until it again bears upon the cloth.

At the same time the pin u descends, releasing the lever t, and permitting the feed-dog to regain its former position by the action of the spring s. (See fig. 3.)

As the needle descends through the cloth a second time, the first loop is thrown off from the shuttle by the bevelled edge e' of the hook e, as shown on fig. 6, and the loop, when thus detached, is prevented from becoming entangled with the driver C by the rod h, which holds it close to the shuttle.

As the needle continues to descend, a second loop is caught by the shuttle-hook, and carried round, the first loop, together with the interlocked shuttle-thread from the bobbin G, being carried up into the cloth.

The second loop is in like manner thrown off from the shuttle, and drawn up and interlocked with the shuttle-thread as a third loop is formed, the operation being repeated and continued until the required number of stitches have been made.

A most important point is the fact that the bobbin G is stationary, and does not revolve with the shuttle, being merely held against it by the plate i. In consequence of this arrangement, the shuttle-thread is not carried around and twisted, but is fed through the holes i, in the same condition in which it is wound on the bobbin, the complicated devices for taking the twist out

of the shuttle-thread, which render machines of this class so objectionable, being entirely dispensed with.

Another plan of holding the bobbin up to the shuttle is illustrated in fig. 8. In this case the bobbin is contained within a cup-shaped plate, i, which is held in its place by a light spring rod, y, secured to the under side of the bed-plate, the pressure of which rod is, however, not sufficient to prevent the free passage of the loop of needle-thread between it and the cup.

Although the thread which passes through the openings in the plate i will generally prevent the latter from turning, it may be rendered more secure by a finger, W, fig. 1, extending from the base-plate A, and bearing against a projecting portion of the plate i, the needle-thread passing between the finger and the plate as it is carried round the shuttle.

On account of the adjustability of the hook e, its position in regard to the points of the shuttle may be regulated with the nicety required.

By operating the presser-foot and feeding-dog from the rear end of the machine, the presence of operating-devices over the work-plate, where they interfere with movements of the operator, is avoided.

I claim as my invention, and desire to secure by Letters Patent—

1. A shuttle, F, having a hook, d, at the edge, and a hook, e, at the back, and revolving in an inclined shuttle-race, in combination with a bobbin, G, which lies within a perforated case, retained in a stationary position loosely within the shuttle, as described.

2. The hook e, bevelled at the edge, arranged at the back of the shuttle, so as to be adjustable on the same, and operating substantially as specified.

3. A projection, f, arranged in respect to the shuttle, substantially as and for the purpose set forth.

4. The presser-foot, attached to an arm vibrating on a fulcrum at the rear end of the machine, and operated by the needle-arm, as described.

5. A feeding-foot, K, attached to an overhanging arm, pivoted at the rear end of the machine, and operated vertically and laterally from the needle-arm by devices substantially as described, and for the purpose specified.

6. The arm I, hung to the base-plate A, and carrying the arm L and slide r, in combination with a wedge, q', which is forced between the slide and the arm L on the movement of the needle-arm, substantially as and for the purpose specified.

In testimony whereof, I have signed my name to this specification, in the presence of two subscribing witnesses.

Witnesses:

JOHN WHITE,

HARRY SMITH.
